United States Patent

Des. 237,061
Patented Oct. 7, 1975

237,061

BASE FOR ANNULAR TEMPLATE AND SCRIBER

Hyok Sang Lew, 1620 E. Blacklidge Drive 6,
Tucson, Ariz. 85719

Filed May 29, 1973, Ser. No. 364,877

Term of patent 14 years

Int. Cl. D10—99; D19—06

U.S. Cl. D10—61

Fig. 1

FIG. 1 is a top perspective view for a base for an annular template and scribe showing my new design;

FIG. 2 is a top plan view thereof;

FIG. 3 is a bottom plan view thereof;

FIG. 4 is a right end elevation view thereof; and

FIG. 5 is a left end elevation view thereof.

I claim:

The ornamental design for a base for annular template and scribe, as shown.
